UNITED STATES PATENT OFFICE.

DAVID C. STEPHENSON, OF TOLEDO, OHIO, ASSIGNOR TO THE NATIONAL MALLEABLE CASTINGS COMPANY.

TRACK-ANCHOR.

1,100,926.

Specification of Letters Patent. Patented June 23, 1914.

Application filed April 15, 1913. Serial No. 761,255.

To all whom it may concern:

Be it known that I, DAVID C. STEPHENSON, a citizen of the United States, residing at Toledo, Lucas county, Ohio, have invented 5 a new and useful Improvement in Track-Anchors, of which the following is a specification, reference being had to the accompanying drawings, in which—

Figure 1 shows an elevation of my device 10 applied to the base of a rail; Fig. 2 is a plan thereof; Fig. 3 is a side elevation thereof; Fig. 4 is a detail of the wedge member; Fig. 5 shows an elevation of a modified form of 15 my device, Fig. 6 a plan thereof, Fig. 7 a side elevation, and Fig. 8 a section on lines VIII—VIII of Fig. 5.

My invention relates to anchors for railroad tracks and is designed to provide a simple, effective and positive means for anchoring the rail to the trackway, and to prevent 20 the rail from creeping.

My invention also consists in the construction and coöperation of the parts which I shall hereinafter describe and claim.

25 Referring to the drawings, A indicates the rail, B the fastener plate, C the wedging member and D the tie. The fastener plate has on one end a lip 2 adapted to engage a base flange 3 of the rail A and at the other 30 end a projection 4 having an undercut face 5 extending longitudinally of the plate and inclined toward the web of the rail. The wedge C is adapted to engage the other flange 3' of the rail A and has a lip 6 over- 35 lying the same. The face 7 of the wedge opposite the lip 6 is inclined to coöperate with the undercut face 5 of the projection 4. Depending from the broad end of the wedge is an abutment 8 adapted to bear against the 40 tie D, and 9 is a strengthening web connecting the abutment and the wedge. The forward end 10 of the wedge C is reduced and is adapted to be bent to coöperate with the curved or inclined keyway 11 in the projection 4. The numeral 12 indicates a driving 45 boss on the fastener plate B.

My device is assembled as follows: I pass the plate B underneath the rail base in such manner that the lip 2 will engage the base 50 flange 3 of the rail. I then insert the smaller end of the wedge into the guideway between the undercut face 5 of the projection 4 and the base flange 3' of the rail, and move the plate and the wedge C toward the tie D in 55 such manner that the abutment 8 will en-

gage against the side of the tie D. I then drive the fastener plate B back on the wedge C by sledging against the boss 12. This causes the wedge to move relatively forward in the guideway between the face 5 and the 60 base 3' of the rail flange and to wedge the rail solidly between the lip 2 and the inner face of the wedge. At the same time the bendable end 10 of the wedge C will engage the curved keyway 11 and will bend there- 65 through, thus locking the wedge securely in the position in which it has been driven between the projection 4 and the rail flange 3', which will thus prevent either the wedge or the plate from becoming loosened from 70 their engagement with the rail.

It will be seen that the longitudinal thrust of the rail will simply force the wedge farther into its guideway between the projection 4 and the rail flange 3', and that 75 such movement will merely serve to tighten and make more secure the engagement of the anchor with the rail. If it becomes necessary at any time to remove the anchor, this can be done by sledging the abutment 80 13, positioned on the upper surface of the projection 4, in the opposite direction from that in which it is driven upon the wedge. This will force the bent end 10 out of the curved guideway 11 and release the anchor 85 from its engagement with the rail.

In Figs. 5 to 8 I show a modified form of 90 my device, in which the bendable locking means 10' is made separate from the wedge and coöperates with a curved guideway 11' in the projection 4. This bendable locking member 10' has a head 14, which engages the rear face 15 of the wedge and holds it in locking position when the member 10' has been driven home in its keyway 11'.

95 It is obvious that my invention is not limited to the particular form of fastener and key members shown herein, since

What I claim is:

1. In a track anchor, a fastener plate 100 adapted to engage one flange of the rail, a rail-engaging member adapted for insertion between the other flange of the rail and the plate, the said members being adapted to be brought into wedging engagement with each other and with the rail by movement of the plate in a direction longitudinal of the rail, the said rail-engaging member having an abutment adapted to take against the tie, one of said members having in co- 110

operation therewith bendable locking means adapted to be bent through an inclined keyway on the other of said members.

2. In a track anchor, a plate adapted to engage one flange of the rail, a tie-engaging member having an extension for insertion between a flange of the rail and the fastener plate, a keyway in the fastener plate, bendable locking means coöperating with said tie-engaging member adapted to be bent in said keyway for locking the said tie-engaging member in wedging engagement with the rail and fastener plate.

3. In a track anchor, two members movable longitudinally of the rail for engaging opposite flanges thereof, one of said members having a tie-engaging portion, a wedge portion, one side of the wedge portion engaging a rail flange and the other side engaging the other member, and a bendable locking portion, the bendable locking portion coöperating with a curved guideway on the other of said members.

4. In a track anchor, a fastener plate having a plurality of projections on the upper

face thereof, one of said projections being adapted to grip a flange of the rail, a wedge adapted to be driven between the other projection and the other flange of the rail, the said wedge having an abutment for engagement with a tie, and bendable locking means coöperating with said wedge and a keyway for locking together the fastener plate, the wedge and the rail.

5. In a track anchor, two members movable longitudinally of the rail for engaging opposite flanges thereof, one of said members having a plurality of upwardly-extending projections, one of which is adapted to engage a rail-flange, the other member having a tie-engaging portion, a wedge portion adapted to engage an upwardly-extending projection of the other member and a bendable locking portion coöperating with a curved guideway on the other of said members.

DAVID C. STEPHENSON.
